UNITED STATES PATENT OFFICE.

HERBERT O. SHARPE, OF BROOKLYN, NEW YORK, ASSIGNOR TO ABRAHAM G. JENNINGS AND ALBERT G. JENNINGS, OF SAME PLACE.

DESIGN FOR A PATTERN FOR LACE.

SPECIFICATION forming part of Design No. 24,645, dated August 27, 1895.

Application filed July 24, 1895. Serial No. 557,027. Term of patent 7 years.

To all whom it may concern:

Be it known that I, HERBERT O. SHARPE, a citizen of the United States, residing in Brooklyn, Kings county, and State of New York, have invented and produced a new and original Design for a Pattern for Lace, of which the following is a specification, reference being had to the accompanying drawing, in which the figure shows a face view of a portion of lace embodying my design.

The essential features of my design consist in checker-board patterns having a chevroned-like pattern interposed between the same and being bordered with a floral-like design.

In the drawing, *a b* represent the checker-board patterns which have a chevroned-like design *c* interposed between the same, the checker-board pattern *b* being bordered with floral-like patterns *d e*. 20

It will be understood that the essential features of my design appear upon a suitable background *f*.

What I claim is—

The design for a pattern for lace, substantially as herein shown and described. 25
